7 Claims

ABSTRACT OF THE DISCLOSURE

This invention relates to a method for the preparation of alkyl 7-hydroxy-2,5-heptadienoates and dialkyl 2,5,8-decatriene-1,10-dioates by the reaction of 2-butene-1,4-diol, acetylene, nickel carbonyl, carbon monoxide, an alkanol of one to eight carbon atoms, an acid, and a halide, where the acid is an organic acid of one to eight carbon atoms, phosphoric acid, phosphorous acid, or boric acid, and the halide is a bromide or iodide of the alkali metals, lithium chloride, or the iodide of the alkaline earth metals.

This invention deals with a method for producing specific hydroxy monoesters. It further deals with a method for producing specific diesters. It more particularly deals with a method for preparing alkyl 7-hydroxy-2,5-heptadienoates and dialkyl 2,5,8-decatriene-1,10-dioates.

The present process involves a reaction employing 2-butene-1,4-diol, acetylene, nickel carbonyl, carbon monoxide, a defined alkanol, a defined acid and a defined halide.

The hydroxy esters produced by the process of the present invention are the alkyl 7-hydroxy-2,5-heptadienoates, the alkyl portion depending directly on the alkanol employed in the reaction. These esters have known utilities, for instance, to form polyesters and polyamides, which are useful as films or fibers. They may also be hydrogenated to form the corresponding saturated ester or further reacted under the circumstances of the present invention to form dialkyl 2,5,8-decatriene-1,10-dioates which have known utilities, particularly in the fiber field, such as for garments, tires and others.

Many attempts have been made in the prior art to produce the alkyl 7-hydroxy-2,5-heptadienoates and dialkyl 2,5,8-decatriene-1,10-dioates. Various degrees of success have been reported but all previous attempts have been plagued by substantial competing reactions which inevitably lead to large amounts of undesired side products or no reaction at all. By rigidly adhering to the teachings of the present invention, one consistently achieves good yields of desired product.

The alkanols used in the present process are those containing from one to eight carbon atoms and may be straight or branched chain in any of the known spatial configurations. It is preferred to use the lower alkanols, such as from one to four carbon atoms and especially methanol. Typically, there may be employed methanol, ethanol, isopropanol, butanol, hexanol, 2-ethylhexanol, octanol and the like. It is preferred to employ methanol or ethanol.

In addition to 2-butene-1,4-diol, which is the preferred reactant, there may be employed 2,3-dialkyl substituted 2-butene-1,4-diols. These alkyl substituents should contain no more than four carbon atoms each, preferably one to two carbon atoms. It is possible to have just one alkyl substituent. These alkyl embodiments include methyl, ethyl, propyl or butyl. With the propyl or butyl em-

2

bodiments, it is preferred to employ the straight chain configurations.

The acid employed includes organic acids of one to eight carbon atoms, such as formic, acetic, butanoic, octanoic, benzoic and the like. There also may be employed phosphoric acid, phosphorous acid and boric acid. The preferred acid is phosphoric. In this respect, it is emphasized that strong acids, such as hydrochloric and sulfuric acids, do not react according to the teachings of the present process.

To conduct the reaction of the present invention, one adds, as desired, the various defined reactants, preferably substantially simultaneously. In some instances, it is preferable to react the 2-butene-1,4-diol with the defined acid to form a diester and then continue the reaction with the remainder of the defined reactants. Such a modification is within the gamut of this invention.

The halide employed comprises the bromides and iodides of the alkali metals, lithium chloride and the iodides of the alkaline earth metals. Typically, these include sodium iodide, sodium bromide, potassium iodide, potassium bromide, lithium chloride, lithium iodide, lithium bromide, calcium iodide, barium iodide and strontium iodide. The preferred embodiments are calcium iodide, lithium chloride, lithium bromide and sodium bromide.

The present reaction is conducted at a temperature of 25° to 75° C., preferably 40° to 60° C. Atmospheric pressure is perfectly satisfactory although increased pressures may be employed, if desired.

The halide is employed in the range of 0.01 mole per mole of the diol to 1.0 mole per mole of the diol, preferably 0.05 to 0.20 mole per mole of the diol.

The acetylene is employed in the range of 0.3 mole per mole of diol to 3.5 moles per mole of the diol, preferably 1.0 to 2.0 moles per mole of the diol.

The acid is employed in the range of 0.2 mole per mole of diol to 2.0 moles per mole of the diol, preferably 0.3 to 0.7 mole per mole of the diol.

The nickel carbonyl is employed in the range of 0.25 mole per mole of the diol to 1.0 mole per mole of the diol.

Carbon monoxide is supplied to the reaction system entirely or principally, as desired, through the agency of nickel carbonyl.

In many instances, carbon monoxide gas, in addition to the carbon monoxide supplied by the nickel carbonyl, is advantageously added to the reaction system. In such instances, there may be employed amounts up to about 0.8, preferably 0.5 to 0.75, mole of carbon monoxide per mole of the diol.

During the course of the present reaction, both alkyl 7-hydroxy-2,5-heptadienoate and dialkyl 2,5,8-decatriene-1,10-dioate are formed. The formation of the monoester is favored by shorter reaction times and the use of the lower molar ranges of acid, acetylene and halide. At the same time, the total yield of both products is reduced. The use of longer reaction times and higher molar amount of acid, acetylene and halide favors a higher yield of the diester and a higher total yield of products.

At the conclusion of the reaction, the product (both monoester and diester) is isolated by stripping unused, volatile reactants and extracting the remainder with a suitable extractant, such as diethyl ether and water. The product is found in the ether layer, which may then be isolated by standard distillation techniques, preferably under reduced pressure.

The present process may be more fully understood from the following examples, which are offered by way of illustration and not by way of limitation.

EXAMPLE 1

A solution of 44 g. (0.5 mole) 2-butene-1,4-diol and 29.4 g. phosphoric acid (aqueous 86%, 0.3 mole) made up to 240 cc. with methanol was charged to a 1-liter continuous flow stirred tank reactor. The reactor was flushed with nitrogen and maintained at 45° C. A solution of $\text{Ni}(\text{CO})_4$ in methanol was fed at a rate of 0.31 mole/hour of $\text{Ni}(\text{CO})_4$ and a solution of NaBr in methanol was fed at a rate of 0.27 mole/hour of NaBr. Initially, acetylene and carbon monoxide were fed at 0.56 mole/hour and 0.14 mole/hour, respectively. After the reaction had initiated (as evidenced by an exotherm and the appearance of a red color), the various feeds were maintained at the following rates: $\text{Ni}(\text{CO})_4$ at 0.31 m./hour, NaBr at 0.27 m./hour, acetylene at 1.03 m./hour, carbon monoxide at 0.2 m./hour, cis-butenediol at 0.5 m./hour, phosphoric acid at 0.31 m./hour and methanol at 20 m./hour. The reaction was maintained for eight hours at which time a sufficient number of reactor volume turnovers had occurred to ensure obtaining an equilibrium sample for workup. The material in the reactor was filtered, stripped of $\text{Ni}(\text{CO})_4$ and methanol under reduced pressure, and the residue extracted with ether and water. Analysis of the aqueous layer showed 0.15 mole of $\text{Ni}^{++}/0.5$ mole butenediol reacted. The ether layer was dried with Na_2SO_4 , filtered and distilled under reduced pressure to give two major products. The first was methyl 7-hydroxy-2,5-heptadienoate, B.P. 90° C. n_{D}^{20} 1.4870, identical in infrared and NMR spectra with an authentic sample prepared by a different route and which gave the following elemental analysis: calculated for $\text{C}_8\text{H}_{12}\text{O}_3$: C (61.40%, theory 61.52%), H (7.67%, theory 7.75%) and O (31.25%, theory 30.73%). The second product was dimethyl 2,5,8-decatriene-1,10-dioate, B.P. 0.1 mm., 96° C., n_{D}^{20} 1.4896, infrared spectrum (liquid smear): strong bands at 1715 to 1730 cm^{-1} , 1435 cm^{-1} , 1400 cm^{-1} , 968 cm^{-1} and 815 cm^{-1} .

Analysis.—Calculated for $\text{C}_{12}\text{H}_{16}\text{O}_4$: C (64.35%, theory 64.27%), H (7.32%, theory 7.19%) and O (28.81%, theory 28.54%).

A sample was hydrogenated to give, after purification, a compound identical with dimethyl sebacate. The first product was obtained in 29% conversion and the second in 34% conversion, both based on the butenediol.

EXAMPLE 2

A series of experiments was performed in which a solution of 0.95 mole 2-butene-1,4-diol in 300 cc. of methanol was charged to a one-liter reactor. Separate feeds of halide, acid, $\text{Ni}(\text{CO})_4$, acetylene, carbon monoxide and additional methanol were then maintained for a period of 1 to 2 hours. The results are given in the table.

TABLE

	Runs

³ Benzoic acid.

⁴ Trifluoroacetic acid.

EXAMPLE 3

A solution of 0.12 mole LiBr in 250 cc. anhydrous ethanol was charged to 1-liter reactor. The temperature was held at 55° C. while a total of 0.6 mole of 1,4-diacetoxy-2-butene (prepared preliminarily by reacting acetic acid with 2-butene-1,4-diol), 0.4 mole of $\text{Ni}(\text{CO})_4$, 1.5 moles acetylene, 0.45 mole of carbon monoxide and 300 cc. anhydrous ethanol were fed to the reactor. Ethanol and $\text{Ni}(\text{CO})_4$ were stripped off under reduced pressure and the residue extracted with ether and water. The ether layer was dried with Na_2SO_4 and stripped of ether. The residue could not be distilled without decomposition. Pure product was isolated, however, from a preparative gas-liquid chromatograph. Diethyl 2,5,8-decatriene-1,10-dioate (65% yield) was obtained.

Analysis.—Calculated for $\text{C}_{14}\text{H}_{20}\text{O}_4$: C (66.31%, theory 66.60%) and H (7.94%, theory 7.95%).

What is claimed is:

1. A process for the preparation of alkyl 7-hydroxy-2,5-heptadienoate and dialkyl 2,5,8-decatriene-1,10-dioate, in which the alkyl contains from one to eight carbon atoms, comprising reacting at a temperature of about 25° to 75% 2-butene-1,4-diol, about 0.3 to 3.5 moles of acetylene per mole of said diol, about 0.25 to 1.0 mole of nickel carbonyl per mole of said diol, carbon monoxide, an alkanol of one to eight carbon atoms, about 0.2 to 2.0 moles of an acid per mole of said diol, and about 0.01 to 1.0 mole of a halide per mole of said diol, wherein said acid is an organic acid of one to eight carbon atoms, phosphoric, phosphorous or boric acids and wherein said halide is a bromide or iodide of the alkali metals, lithium chloride or the iodide of the alkaline earth metals.
2. The process according to claim 1 wherein the reaction is conducted within the range of about 40° to 60° C. and there are employed:
  - about 0.05 to 0.20 mole of said halide per mole of the diol,
  - about 1.0 to 2.0 moles of said acetylene per mole of the diol,
  - about 0.3 to 0.7 mole of said acid per mole of the diol, and
  - about 0.25 to 1.0 mole of said nickel carbonyl per mole of the diol.
3. The process according to claim 1 wherein there is employed up to about 0.8 mole of carbon monoxide gas per mole of the diol.
4. The process according to claim 1 wherein said alkanol is methanol, said acid is phosphoric and said halide is lithium bromide.
5. The process according to claim 1 wherein said alka-

5

nol is ethanol, said acid is phosphoric and said halide is sodium bromide.

6. The process according to claim 1 wherein said alkanol is methanol, said acid is benzoic and said halide is sodium iodide.

7. The process according to claim 1 wherein said alkanol is methanol, said acid is phosphoric and said halide is calcium iodide.
